UNITED STATES PATENT OFFICE

138,832

DESIGN FOR A COOKIE JAR OR SIMILAR ARTICLE

Frances Poe, Wilmette, Ill.

Application July 20, 1944, Serial No. 114,482

Term of patent 7 years

(Cl. D58—25)

To all whom it may concern:

Be it known that I, Frances Poe, a citizen of the United States, residing at Wilmette, in the county of Cook and State of Illinois, have invented a new, original, and ornamental Design for a Cookie Jar or Similar Article, of which the following is a specification, reference being had to the accompanying drawing, forming a part thereof.

I claim:

The ornamental design for a cookie jar or similar article, substantially as shown.

FRANCES POE.
